[57] CLAIM

The ornamental design for a truck bed insert permitting retrieval of goods within truck bed, as shown and described.

DESCRIPTION

FIG. 1 is a perspective view of the truck bed insert permitting retrieval of goods within truck bed showing my new design;

FIG. 2 is a front elevational view thereof;

FIG. 3 is a rear elevational view thereof;

FIG. 4 is a right side elevational view thereof, the left side elevational view being a mirror image of the view shown in this Figure;

FIG. 5 is a top plan view thereof;

FIG. 6 is a bottom plan view thereof; and,

FIG. 7 is a perspective view of the truck bed insert installed in a truck bed.

The broken line illustration in FIG. 7 represents a truck bed and a portion of a truck and is not part of the design sought to be patented.
